SUCTION CLEANER

William H. Kitto, Canton, Ohio, assignor to The Hoover Company, North Canton, Ohio, a corporation of Ohio

Application February 11, 1935, Serial No. 5,912.
Renewed December 10, 1936. In Great Britain
April 10, 1934

7 Claims. (Cl. 15—6)

The present invention relates to suction cleaners in general and particularly to new and novel improvements in means to convert a suction cleaner from an on-the-floor cleaning unit to an off-the-floor cleaning unit. More specifically the invention comprises the provision of an improved permanently embodied converter mechanism in a suction cleaner.

It is an object of the present invention to provide a suction cleaner embodying new and improved conversion means. A still further object is the provision, in a suction cleaner, of a new and novel converter valve construction which is adapted to convert the cleaner from an on-the-floor cleaning unit to an off-the-floor cleaning unit. Still another object is the provision of a new and improved dusting-tool-actuated converter valve in a suction cleaner. A still further object is the provision, in a suction cleaner, of a permanently incorporated converter valve which automatically converts the cleaner from an on-the-floor cleaning unit to an off-the-floor cleaning unit upon the connection to the cleaner proper of a dusting tool unit, and which further automatically reconverts the cleaner to an on-the-floor cleaning unit upon the detachment of the dusting tool unit. These and other more specific objects will appear upon reading the following specification and claims and upon considering in connection therewith the attached drawings to which they relate.

Referring now to the drawings in which preferred embodiments of the present invention are disclosed;

Figure 1 is a side elevation of a suction cleaner embodying the present invention with a dusting tool unit connected thereto, certain parts being broken away;

Figure 2 is a bottom view of the cleaner shown in Figure 1 with certain parts broken away to show the invention more clearly;

Figure 3 is a section through the converter construction upon the line 3—3 of Figure 2;

Figure 4 is a section at right angles to Figure 3 upon the line 4—4 of Figure 2;

Figure 5 is a partial bottom view of the cleaner, similar to Figure 2, but with the dusting tool unit removed and the valve in its on-the-floor cleaning position;

Figure 6 is a partial bottom view of a suction cleaner embodying a second preferred embodiment of the invention with the dusting tool unit attached and the valve in its off-the-floor cleaning position.

Figure 7 is a section through the cleaner upon the line 7—7 of Figure 6;

Figure 8 is a section at right angles to Figure 7, being taken upon the line 8—8 of Figure 6;

Figure 9 is a view similar to Figure 6, but with the dusting tool unit removed and the valve positioned for on-the-floor cleaning.

In the drawings a modern suction cleaner is disclosed. The cleaner body comprises a nozzle 1, a fan chamber 2, and an exhaust outlet 3. The interior of the nozzle is connected to the eye 4 of the fan chamber by an air passageway 5, and functions to convey air therebetween in response to the suction created by the fan 6 which is positioned within the fan chamber 2, being carried by the motor shaft 7 which is extended into the air passageway. The nozzle is provided with front and rear lips 8 and 9 which are adapted to contact a surface covering undergoing cleaning and which define the mouth of the nozzle through which cleaning air is drawn. A rotary agitator 10 of a common and well known type which includes rigid surface-contacting elements and flexible brush elements is rotatably mounted within the nozzle and is adapted to contact a surface covering between the lips 8 and 9 to assist in dislodging foreign matter therefrom. Agitator 10 is rotated by a power-transmitting belt 11 which extends thru the passageway 5 to a pulley surface formed at the lower end of motor shaft 7. A motor casing 12 is positioned above the fan chamber 2 and houses an unshown driving motor of which the shaft 7 is a part. At the end of the exhaust outlet 3 is connected a removable dust bag 29 which functions, in the operation of the machine, to filter from the air which passes therethrough the suspended foreign matter removed from the surface covering. Spaced pairs of front and rear wheels 13, 13 and 14, 14 movably support the cleaner, the front wheels, being positioned within wheel pockets 15, 15 at the sides of the air passageway 5 within the nozzle casing and immediately in the rear of the nozzle 1. As in the usual cleaner construction a pivoted handle 16 is provided by which the operator may exert a propelling force to move the cleaner.

With the machine altered for off-the-floor cleaning, a dusting tool unit comprising a dusting tool nozzle 17, a flexible elongated hose 18, and a metallic connector or seat 19, is suitably secured to the suction cleaner so that the suction created by the suction-creating means is effective to draw cleaning air through the dusting tool unit instead of through the cleaner nozzle. The means by which the conversion of the cleaner from an on-

the-floor cleaning unit to an off-the-floor cleaning unit is accomplished upon the attachment of the dusting tools comprises the present invention.

Referring now to Figures 1 to 5, inclusive, the 5 first preferred embodiment of the invention is disclosed.

At the side of the air passageway 5 adjacent the eye 4 of the fan chamber is positioned a conduit 20. This conduit is in effect a second air 10 passageway and is adapted to receive and seat the metallic seat member 19 formed on the inner end of the dusting tool hose 18. Cooperating means comprising a spring-pressed detent 21 carried by the seat 19 and a detent seat 22 formed in the 15 conduit cooperate to secure the parts against accidental displacement. The opening of conduit 20 into the air passageway at the fan chamber eye is normally closed by a valve 23 which is pivoted adjacent the side wall of the passageway 20 5 forward of the conduit and is spring-pressed into conduit-closing position by a coil spring 24 positioned at the pivot point. Valve 23, as is clearly seen in Figures 2 and 5, is shaped somewhat in the form of a letter U with flared ends. 25 To accommodate the valve in its conduit-closing position the wall of the air passageway 5 immediately in the rear of the conduit 20, that is upon the side farthest spaced from the nozzle end of the cleaner, is recessed outwardly, as at 30 28, to form a valve seat. The valve in its conduit-closing on-the-floor position is illustrated in Figure 5.

Upon the insertion of the metallic seat 19 of the dusting tool into the conduit 20 the valve 35 23 is contacted and pivoted from the position shown in Figure 5 to the position shown in Figure 2. In this second position it extends around the motor shaft 7 and into contact with the opposite side wall of the air passageway 5. The 40 valve extends from the upper wall of the air passageway, formed by the bottom of the fan chamber 2, to the lower wall thereof and cuts off from the nozzle the greater portion of the fan chamber eye. A permanent closure plate 45 26 extends from the normal circular contour of the eye 4 of the fan chamber out to and partially around the motor shaft 7 to close to the nozzle that part of the normal fan eye forward of the valve 23. It is clear that thru the 50 operation of the valve 23 and the plate 26 no air can enter the fan chamber from the nozzle. With the valve in this nozzle-sealing position, as shown in Figure 2, the conduit 20, and so the 55 dusting tool unit, is directly connected to the fan chamber through being open to the eye 4 thereof.

To insure the sealing contact of the valve in its nozzle-closing or air-passageway-closing position, with the opposite wall of the air passageway, and to prevent any binding, a leaf contact spring 27 is provided on the outer side of the valve 23 in a position in which it is adapted to be contacted by the forward edge of the metallic seat member 19, that member being cut 60 upon an angle at its end, as seen in Figure 2, to prevent any possible overlapping of the eye of the chamber. With the forward edge of the seat member in contact with the valve, the valve is urged into sealing relationship with the opposite wall of the air passageway and with the seat 19 being locked in place the valve is also seated. Upon the withdrawal of the dusting tool unit, an operation which requires only the manual release of the spring-pressed detent 21 and 65 the outward displacement of the seat member,

the valve is again forced to its original position, shown in Figure 5, by the coil spring 24.

Referring now to Figures 6 to 9, inclusive, a second preferred embodiment of the invention is disclosed. In this embodiment the general 5 construction of the suction cleaner is as described in the first embodiment. The differences which exist are found in the conversion mechanism. According to the present embodiment a housing 30 is provided in the air passageway 10 5, and at the eye of the fan chamber, which extends downwardly from the top wall of that passageway, as formed by the underside of the fan chamber, to the bottom wall of the passageway and encloses the lower end of the driving 15 shaft 1 where it connects with the power-transmitting belt 11. Housing 30 opens interiorly to the air passageway forward of the eye of the fan chamber and permits of the unhindered entrance of the belt 11 to the motor shaft which 20 extends downwardly through an opening in the top thereof. The top of the housing, except at its forward edge, is spaced below the plane of the fan chamber eye so that air which has passed the forward end of the housing can pass thereover and into the chamber. A minimum of restriction to the eye results from this construction.

As in the previous embodiment a conduit 20 is provided at the side of the air passageway 5 adjacent the fan chamber eye 4 and is normally closed by a movable valve. In the present instance the valve is a flat plate and is indicated by the reference character 31. As in the previous embodiment, however, the valve is pivoted immediately forward of the conduit upon a pivotal axis which is substantially parallel to the motor axis and is normally spring-pressed into conduit-closing position by a spiral coil spring 32. A contact leaf spring 33, adapted to be contacted by the inserted end of the dusting tool unit, is also provided.

According to this second embodiment of the invention, with the cleaner in on-the-floor cleaning relationship the valve is positioned in conduit-closing relationship as shown in Figure 9, being held in that position by the coil spring 32. The insertion of the end of the dusting tool unit, as in the previous embodiment, functions to pivot the valve to open the conduit 20 and connect it and the dusting tool hose unit seated therein to the eye 4 of the fan chamber. The valve pivots forwardly from the position shown in Figure 9 to that shown in Figure 6 in which position it seats upon a shoulder 34 where it is held by the contact of the metallic seat 19 of the dusting tool unit with the leaf contact spring 33 of the valve. The valve now cooperates with housing 30 to seal completely the nozzle from the eye of the fan chamber. The conduit 20 and its seated dusting tool hose unit, on the other hand, is directly connected to the eye of the fan chamber, and in the operation of the machine cleaning air is drawn therethrough. As in the previous embodiment the reconversion of the machine to 65 an on-the-floor cleaning unit is simply the reverse operation.

I claim:

1. In a suction cleaner, a body including a nozzle, a fan chamber and an air passageway 70 therebetween, and a motor-driven fan in said chamber; a conduit opening into said passageway at the eye of said fan chamber, a valve normally closing said conduit, fixed means closing a part of said fan chamber eye from said nozzle, said

valve being movable from its conduit-closing position to a passageway-closing position in which it cooperates with said fixed means in closing said nozzle from said fan chamber, said conduit being adapted to receive and seat the end of a dusting tool unit and said valve being adapted to be contacted and moved thereby from said conduit-closing position to said passageway-closing position.

2. In a suction cleaner having a body including a nozzle, an air passageway extending from said nozzle, a fan chamber having an eye opening into said passageway, and a motor-driven fan in said chamber, a rotating motor part extended thru said chamber into said passageway and carrying said fan in the chamber, a surface covering agitator in said nozzle, and power transmission means extended from said agitator thru said passageway and connected to said rotating motor part; stationary means extending to said motor part and obstructing a portion of said fan chamber eye, a dusting-tool-receiving conduit opening into said passageway at said eye, a valve normally closing said conduit and adapted to be contacted by a dusting tool connected thereto and movable by said contact into a position in which it extends across said eye to cooperate with said stationary means in closing said fan chamber to said nozzle.

3. In a suction cleaner having a body including a nozzle, an air passageway extending from said nozzle, a fan chamber having an eye opening into said passageway, and a motor-driven fan in said chamber, a rotating motor part extended thru said chamber into said passageway and carrying said fan in the chamber, a surface covering agitator in said nozzle, and power transmission means extended from said agitator thru said passageway and connected to said rotating motor part; stationary closure means extending to said rotating motor part between it and said nozzle and obstructing a portion of said fan chamber eye, a dusting-tool-unit-receiving conduit open to said passageway at said eye, a pivoted valve normally closing said conduit and movable to a second position to cooperate with said closure means in sealing said nozzle from said fan chamber, said valve being arranged so as to be contacted by the end of a dusting tool unit when in conduit-closing position and to be pivoted thereby into its second position.

4. In a suction cleaner having a body including a nozzle, an air passageway extending from said nozzle, a fan chamber having an eye opening

into said passageway, and a motor-driven fan in said chamber, a rotating motor part extended thru said chamber into said passageway and carrying said fan in the chamber, a surface covering agitator in said nozzle, and power transmission means extended from said agitator thru said passageway and connected to said rotating motor part; a stationary housing enclosing the junction of said power transmission means and said rotating motor part and preventing the direct flow of air from said nozzle to said fan chamber eye, a dusting-tool-unit-receiving conduit open to said passageway at said eye, a valve normally closing said conduit and movable to a second position to cooperate with said housing to completely seal said nozzle from said fan chamber, said valve being arranged so as to be contacted by the end of a dusting tool unit when in conduit-closing position and to be pivoted thereby into its second position.

5. The construction set forth in the preceding claim characterized in that means are provided to retain said valve against accidental displacement in its conduit-closing position and to return it to said position upon the removal of the dusting tool unit from said conduit.

6. In a suction cleaner having a body including a nozzle, an air passageway extending from said nozzle, a fan chamber having an eye opening into said passageway, and a motor-driven fan in said chamber, a rotating motor part extended through said chamber into said passageway and carrying said fan in the chamber, a surface covering agitator in said nozzle, and power transmission means extended from said agitator thru said passageway and connected to said rotating motor part; a dusting-tool-unit connection open to said passageway at said eye, a U-shaped valve pivoted at one side of said connection and normally extending thereacross to seal said connection from said eye, said valve being movable to a second position in which it extends across the eye of said fan chamber and partially surrounds said rotating motor part, and means cooperating with said valve to surround completely said part and to seal said eye from said nozzle.

7. The construction recited in the preceding claim in which said cooperating means are stationary and said valve is adapted to be moved to its second position by the connection of a dusting tool unit to said connection.

WILLIAM H. KITTO.
